WELL-BORING APPARATUS

George J. Barrett and Sosthene Robichaux,
Houston, Tex.

Application November 20, 1935, Serial No. 50,729

7 Claims. (Cl. 255—1)

This invention relates to a well boring apparatus.

An object of the invention is to provide equipment of the character described whereby, in the process of completing a well, the well bore already formed may be side-tracked and deepened.

In well drilling the well bore sometimes becomes obstructed by pipe or tools, or other obstructions becoming stuck or lost in the bore. In such event the obstructed bore must be sidetracked in order to deepen the well; or for other reasons it might be desirable to sidetrack the bore, as, for example when it is desired to straighten a crooked hole. In order to sidetrack a bore already formed, it is common practice to locate a whipstock in the well at the point where it is desired to sidetrack, said whipstock having a sloping face at its upper end, and to then lower a milling tool into the well bore, which is deflected by the whipstock and caused to cut through the side of the casing in the well, or, if no casing is in the well, to form a new bore in the walls of the bore alongside the original bore. At the present time during the milling operation the milling tool operates against the sloping face of the whipstock as well as against the opposite side of the casing or wall of the bore. The milling tool often mills off the upper end of the whipstock, forming an abrupt shoulder on which the milling tool rides, and in its operation against the whipstock, the milling tool not only cuts away the face of the whipstock, but also becomes broken and dull, all seriously interfering with and impeding the proper operation of the milling tool.

It is one of the principal objects of this invention to provide a whipstock whose upper or sloping face is formed with a track with a carriage mounted to move along the track as the milling operation proceeds and to support the milling tool in spaced relation to the sloping face of the whipstock and out of contact therewith so that all of the work of the milling tool may be applied to cutting a side hole through the casing or to the formation of a new bore alongside the original bore through which drilling may thereafter proceed.

A further object of the invention is to provide a whipstock having novel means for anchoring the same in a bore having a casing therein, or in an open hole, that is, in a hole or bore which has not been cased up.

A still further object of the invention is to provide means for gradually feeding the milling tool to the work to the end that the full weight

of the drill stem will not be sustained by the milling tool during the milling operation. The feeding means employed, however, may be used as well for feeding the drill to the work during ordinary operations.

With the above and other objects in view, the invention has particular relation to certain novel features of construction, operation and arrangement of parts, examples of which are given in this specification and illustrated in the accompanying drawings, wherein:

Figure 1 shows a side view, partly in section, of a whipstock located in a well casing, showing the milling tool in operation in the process of cutting through the casing.

Figure 2 shows a partial vertical sectional view of the whipstock attached to the milling tool and in the process of being lowered into the well.

Figure 3 shows a cross-sectional view taken on the line 3—3 of Figure 2.

Figure 4 shows a cross-sectional view taken on the line 4—4 of Figure 1.

Figure 5 shows an end view of the sleeve bearing forming a tool carriage.

Figure 6 shows a side elevation thereof.

Figure 7 shows an enlarged vertical sectional view of the lower end of one form of whipstock as anchored in the well casing.

Figure 8 shows a side view thereof taken at right angles to the view shown in Figure 7.

Figure 9 shows a cross-sectional view taken on the line 9—9 of Figure 7.

Figure 10 shows a cross-sectional view taken on the line 10—10 of Figure 7.

Figure 11 shows a side elevation of a type of coupling employed for seating the whipstock.

Figure 12 shows a side view, partly in section, of another type of whipstock specially adapted to be set in the open hole, showing a type of sidetracking tool employed therewith.

Figure 13 shows an enlarged fragmentary elevational view, partly in section, showing the lower end of the whipstock disclosed in Figure 12.

Figure 14 shows a side view, partly in section thereof, taken at right angles to the view shown in Figure 13.

Figure 15 shows a cross-sectional view taken on the line 15—15 of Figure 13.

Figure 16 shows an elevational view of a well boring apparatus showing the feeding means for feeding the milling tool or drill to the work.

Figure 17 shows an enlarged vertical sectional view thereof.

Figure 18 shows a fragmentary side view of a

drilling apparatus showing another form of feeding means, and

Figure 19 shows a fragmentary plan view of the apparatus shown in Figure 18.

5 Referring now more particularly to the drawings wherein like numerals of reference designate similar parts in each of the figures, the numerals 1 and 2, respectively, designate the deflector and the anchor forming a whipstock adapted to be 10 located in a casing 3 set in a well. The anchor 2 is of approximately cylindrical contour and preferably has its lower end tapered, or of an inverted cone-shape, forming a guide 4 to guide the anchor in the casing. At one side the anchor has the 15 upwardly and outwardly tapering face 5, and the abrupt shoulder 6 beneath said face and mounted to ride against said face there is the pipe-engaging jaw 7 whose outer side has the downwardly pitched teeth and whose inner side is tapered to 20 conform to the pitch of the face 5.

Pivoted to the upper end of the jaw 7, there is a latch 8 which is normally held inwardly by the flat spring 9 which presses inwardly thereagainst. The upper end of the latch has the outwardly 25 turned lug 10, and the inward extension 11 for a purpose to be hereinafter explained.

The anchor 2 has the axial bore 12 extending downwardly from the upper end thereof and is also provided with a lateral slot 13 leading outwardly from said bore wherein the latch 8 works.

When the anchor 2 is lowered into the well, as hereinafter explained, and reaches the point at which it is desired to set the whipstock, a downwardly tapering weight 14 may be dropped 35 through the lowering string of pipe and will pass on down through the bore 12 and will engage the inward extension 11 of the latch and force the latch outwardly, and when the lug 10 registers with the joint between adjacent sections of the 40 casing 3, said lug will drop into the joint and the jaw 7 will thereby be held stationary, and upon further downward movement of the anchor 2, the face 5 will ride against the inner face of the jaw 7 and force said jaw outwardly into 45 secure engagement with the casing 3 and the anchor 2 will thus be firmly secured into the casing against downward movement.

At the upper end of the anchor 2 the bore 12 is enlarged and formed with a side slot 15, and 50 seated in this enlarged portion of the bore there is a tubular coupling 16 having an elongated lateral spline 17 which fits into the slot 15 and which is pinned therein by means of the frangible cross-pin 18. A string of tubing may be connected with the upper threaded end of the coupling 16 and the anchor thereby lowered to the desired point in the well and the anchor set, as hereinabove explained.

The anchor 2 is also provided with a downwardly and outwardly tapering face 19 whereon is mounted a wedge-shaped jaw 20 whose outer face has the upwardly pitched teeth, and whose inner face is tapered to conform to the taper of the face 19. This jaw 20 is normally held in 65 upper position, with its upper end abutting the lower end of the spline 17 by means of a frangible pin 21 which extends outwardly from the anchor underneath said jaw.

70 When the anchor 2 is located and secured against downward movement in the casing 3, as hereinabove explained, the weight of the setting string above may be released, causing the coupling 16 to move on downwardly, shearing the pins 18 and 21, and causing the jaw 20 to move

downwardly and outwardly into secure engagement with the casing 3, thus anchoring the anchor 2 against upward movement. The setting string, together with the coupling 16, may then be withdrawn from the well.

The upper end of the anchor 2 has a beveled, or tapering, face 22, and pivotally mounted in recesses 23, 23, in this face, and located on opposite sides of the slot 15, are the dogs 24, 24, whose outer ends are normally held projected out 10 beyond said face by the coil springs 25, 25, against which said dogs are seated.

The lower end of the deflector 1 is approximately cylindrical, and it tapers upwardly, the tapering portion being formed with the deflecting face 26 which is arcuate in cross-sectional contour. The lower end of the deflector is also formed with a flat tapering face 27 which is pitched so as to ride upon the tapering face 22 of the anchor when the deflector is lowered into 20 the well, as illustrated in Figure 1. The face 27 has a transverse notch 28 cut across it, forming the upwardly facing shoulder 29. When the deflector is lowered into the well, as hereinafter explained, and as the face 27 moves down over the 25 face 22, the dogs 24 will be depressed until they register with the notch 28, whereupon said dogs will engage over the shoulder 29 and lock the deflector in place.

The numerals 30, 31, designate milling tools, of 30 any conventional construction, and which are 35 mounted upon, and connected by, the spindle 32, said milling tools being thereby suitably spaced apart. The milling tools may be let down into the well and operated by a suitable tubular stem, or operating string 33. The spindle 32 is mounted to rotate in an elongated bearing 34. This bearing is provided, at its lower end, with a dovetailed tenon 35 which is fitted into and shaped to move along a correspondingly shaped dovetailed groove, or mortise 36 extending longitudinally along the tapering portion of the deflector 1 from its upper to its lower end. This tenon is preferably formed integrally with the bearing 34, and extends out far enough to hold 45 the milling cutter 31 spaced away from the sloping face 26 so as not to contact therewith during the operation of said milling cutter.

When it is desired to lower the deflector into the well, the tenon 35 is located in the upper end 50 of the groove 36 and pinned therein by a frangible cross-pin 37, and as thus assembled, may be then let down into the well until the deflector seats on and is latched to the anchor 2, as hereinabove explained, and the weight of the stem 32 will thereupon shear the pin 37, permitting the milling tools to move on downwardly; they will be deflected outwardly into contact with the casing 3, and upon rotation of the stem 33, a side opening will be cut through the wall of the casing 60 3 opposite the deflector face 26. The upper end of the bearing 34 has an outwardly extending guide 38 whose outer surface is curved to conform to the contour of and to ride against the face 26, and upon downward movement of the milling 65 tool, this guide will ride against the face 26 and will hold the upper milling tool 30 out of contact with the whipstock face and firmly against the opposite side of the casing 3, as is illustrated in Figure 1. The upper milling tool 30 is of somewhat larger diameter than the lower tool 31, so that the upper milling tool will cut through the casing first before the lower tool 31 begins to operate on said casing and thereafter both tools will simultaneously operate to cut openings 70 75 75

through the casing, and as the tool progresses downwardly, the material between the openings will be cut out by the upper tool 30 and the opening made by the lower tool will be enlarged by 5 the one above. A long side opening may thus be cut through the casing 3 and the milling tools will not be injured or dulled by coming into contact with the whipstock and their efficiency will all be expended in forming the side opening through 10 the casing. Thereupon the milling tool may be withdrawn and the ordinary tool attached to the lower end of the stem 33, and this drill and stem may thereafter operate through the side opening of the casing as work in deepening the well 15 progresses.

In the form shown in Figures 12 to 14 inclusive, the upper and lower tools 30a and 31a are earth boring tools and may be of any suitable design for sidetracking into the wall of the bore 20 of an open hole, that is, a hole in which casing has not been set. In this form a deflector 1a has the tapering arcuate face 26, and the channel or mortise 36, as in the form shown in Figures 1 and 2, and the sleeve bearing 34 has the tenon 25 35 which moves in the groove 36, and the guide 38 which moves along the face 26 in the manner and for the purposes hereinabove explained. In both forms the bearing 34, the tenon 35, and the guide 38, form a carriage to support the tools 30, 30, 31, or 30a, 31a, as the case may be, and to hold them out of contact with the deflector face 26 so that said tools will not be dulled or broken or have their efficiency reduced by coming into contact with the whipstock.

35 The type of whipstock shown in Figures 12 and 15 is designed to be set on the bottom of the bore, or on an obstruction in the bore which it is necessary to sidetrack. In this form of whipstock, the numeral 39 designates the anchor whose 40 lower end is formed with the inverted conical shaped guide 40, and whose upper end is reduced on opposite sides and formed with an upstanding tenon 41 whose margins taper upwardly and at the upper end thereof are formed with the 45 upwardly converging bearing faces 42, 42. The tenon 41 also has a row of vertically aligned openings 43. The lower end of the deflector 1a has a transverse slot, or mortise, 44 to receive the tenon 41.

50 Pivots mounted at their upper ends in this slot 41 are the wall hooks 45, 45, whose lower ends are outwardly turned and formed with the wall-engaging prongs 46, 46, having the downwardly converging flat faces 47, 47, arranged to ride against the corresponding faces 42, 42. The wall hooks 45 are normally held retracted, or in inner position, by the flat springs 48 which bear against the outer sides thereof.

55 There are the oppositely arranged spring-seated dogs 49, 49, mounted on opposite sides of the slot 44, and in the lower end of the deflector 1a. The inner ends of these dogs are upwardly and inwardly beveled, as at 50, 50, so that upon downward movement of the deflector 1a relative to the anchor 39, the dogs 49 will be successively forced outwardly so that they may engage in the openings 43 successively from above downwardly. In order to lower a whipstock of this type into the well, the upper end of the tenon may be inserted into the slot 44 and the dogs 49 engaged in the upper opening 43 with the faces 42 bearing against the faces 47, the wall hooks 45 being retracted inwardly. The whipstock may then be pinned to the tenon 35, as shown in Figure 2, 70 and the entire apparatus lowered into the well 75

until the anchor 39 rests on the bottom of the bore, or upon an obstruction in the bore. The deflector 1a will move on downwardly by its own weight, the faces 42 cooperating with the faces 47 to force the prongs 46 of the wall hooks 45 outwardly causing them to penetrate into the walls of the bore, as shown in Figure 12, and the dogs 49 will successively engage in the openings 43 as the deflector 1a moves downwardly, and when it has reached the limit of its downward movement, 10 said dogs 49 will thereafter secure the deflector and anchor firmly together. The wall hooks 46 will hold the whipstock against turning in the bore during the succeeding operation of the tools 30a, 31a. When a whipstock of this type is located in 15 the bore, upon downward movement of the stem 33, the pin 37 will be sheared, as hereinabove stated, and as the stem is further lowered and rotated, the tools 30a, 31a, will be gradually deflected against the side wall of the bore opposite 20 the sloping face 26 and will form a new bore, sidetracking the original bore.

The carriage, hereinabove referred to, will hold the tools 30a, 31a, out of contact with the whipstock during the sidetracking operations. Upon 25 completion of the sidetracking operations, the stem 33 may be withdrawn and a drill attached to the lower end of the stem and let down into the bore, and the well thus deepened to the desired depth.

30 It is desirable that the milling tools, or other tool, attached to the lower end of the drill stem be fed to the work gradually so that said tools will not be subjected to too severe work. Means for gradually lowering the drill stem so as to 35 gradually feed the milling tools, or other tools, to the work, have been provided.

As shown in Figure 16, there is the usual derrick 51 on the floor of which is mounted the usual rotary drilling machine 52 through which 40 the drill stem extends, and by means of which it is rotated. Attached to the upper end of the drill stem, there is the conventional swivel 53 which is connected to the traveling block 54. This traveling block is suspended from the crown 45 block 55 of the derrick by an operating cable 56 which is threaded through the sheaves of the crown block and traveling block in the usual way and which is operated by the cable-winding drum 57 of the conventional draw works, not 50 shown. Connected to the floor of the derrick there is a cylinder 58 in which there is a piston 59 connected to the lower end of the piston rod 60 which works through a stuffing box 61 in the upper end of the cylinder. This piston rod is 55 connected to the cable 56 by means of the cable 62. The cylinder 58 is filled with a liquid and is provided with a leak pipe 63 leading downwardly from the upper end thereof and controlled by a valve 64. Upon beginning milling 60 operations or drilling operations, with the piston 59 at the lower end of the cylinder, the valve 64 may be slightly opened so as to allow the liquid in the cylinder above the piston to gradually leak out, and this will control the rate of 65 descent of the drill stem 33 and the tool at the lower end thereof and the amount of leakage may be regulated by the valve 64 so as to obtain the desired feed of the milling tool or drilling tool.

A modified form of feed-controlling apparatus 70 is shown in Figure 18. In this form, a sprocket wheel 65 is fixed on the shaft of the drum 57 and operating over this sprocket wheel is the sprocket chain 66 which also operates over the sprocket wheel 67 fixed on the shaft 68. This 75

shaft 68 also has a larger sprocket wheel 69 fixed thereon over which the sprocket chain 70 operates. One end of the chain 70 is attached to a cable 71. This cable is wound about the drum 72 which is fixed on the transmission shaft 73 and which is equipped with a brake drum 74 and is arranged to be controlled by a suitable brake mechanism of conventional construction, as 75. The numeral 76 designates an electric motor which is operatively connected with the shaft 73 through the speed reduction transmission 77. The free end of the chain 70 is preferably supported by an inclined guide 78.

During milling, or drilling, operations, the cable 71 is gradually unwound from the drum 72 at a uniform rate of speed, and the rotation of the drum 71 in unwinding the cable 56 is thus controlled so as to gradually allow the drill stem 33 to be lowered, and so as to gradually feed the tool at the lower end of said drill stem to the work. Should the weight of the drill stem 33 be sufficient to cause the cable 56 to unwind from the drum 71 too fast and thus speed up the motor 18, the movement of the drill stem downwardly can be additionally controlled by the brake 75.

The drawings and description disclose what is now considered to be preferred forms of the invention by way of illustration only, while the broad principle of the invention will be defined by the appended claims.

What we claim is:

1. A whipstock comprising an anchor shaped to be lowered into a well, means for fixing the anchor to the wall of the well, a deflector shaped to be lowered into the well and adapted to rest on the anchor, means for attaching the deflector to the anchor, said deflector having a sloping face and a tool guide movably mounted on said face.
2. A whipstock shaped to be lowered into a well and formed of an anchor and a deflector, means for securing the anchor to the wall of the well, means for attaching the deflector to the anchor, said deflector having an upwardly taper-

ing face and also having a longitudinal track, and a tool guide mounted to move along the track.

3. A whipstock shaped to be lowered into a well and comprising an anchor, means on the anchor adapted to be projected outwardly into the wall of the well, a deflector, means carried by the anchor and deflector for attaching the deflector to the anchor in the well, said deflector having a sloping, deflecting face, and a tool guide connected to the deflector and movable along said face.

4. A whipstock shaped to be lowered into a well and comprising an anchor, means on the anchor adapted to be engaged with the wall of the well, a deflector, means carried by the anchor and deflector for attaching the deflector to the anchor in the well, said deflector having a sloping deflecting face and a tool guide movable along said face, and arranged to hold the tool out of contact with said face.

5. A whip stock whose upper end is upwardly and outwardly tapered forming a deflecting face, a carriage movable along said face and having a bearing, a spindle rotatable in the bearing on the carriage, a tool on the spindle above and beneath said bearing.

6. In combination a whip stock whose upper end is upwardly and outwardly tapered forming a deflecting face, a carriage movable along said face, spaced boring tools, a shaft connecting said tools and mounted to rotate on the carriage.

7. In apparatus of the character described a whipstock anchor shaped to be lowered into a pipe and having outwardly converging faces, pipe engaging jaws on said faces, a normally retracted member connected to one jaw and engageable with the pipe to anchor said jaw against downward movement whereby the corresponding face actuates said jaw into engagement with the pipe upon downward movement of the anchor and frangible means normally maintaining the other jaw retracted into inactive position.

GEORGE J. BARRETT.
SOSTHENE ROBICHAUX.
